(57) **CLAIM**

The ornamental design for a pick holder for a stringed instrument, as shown and described.

DESCRIPTION

FIG. 1 is a front, right perspective view of a pick holder for a stringed instrument;

FIG. 2 is a right side view of the pick holder for a stringed instrument;

FIG. 3 is a left side view of the pick holder for a stringed instrument;

FIG. 4 is a front view of the pick holder for a stringed instrument;

FIG. 5 is a rear view of the pick holder for a stringed instrument;

FIG. 6 is a bottom view of the pick holder for a stringed instrument;

FIG. 7 is a top view of the pick holder for a stringed instrument; and,

FIG. 8 is a front, right perspective view of the pick holder for a stringed instrument with an unclaimed texture shown thereon.

The broken lines showing portions of the design are for illustrative purposes only, illustrate unclaimed portions, and form no part of the claimed design.

1 Claim, 5 Drawing Sheets
